UNITED STATES PATENT OFFICE.

ALFRED H. DAVIES, OF AKRON, OHIO.

GAS-HEATED SAD-IRON.

973,011.

Specification of Letters Patent. Patented Oct. 18, 1910.

Application filed January 4, 1910. Serial No. 536,328.

To all whom it may concern:

Be it known that I, ALFRED H. DAVIES, a citizen of the United States, residing at Akron, in the county of Summit and State of Ohio, have invented a new and useful Gas-Heated Sad-Iron, of which the following is a specification.

In gas heated sad-irons it is a well known fact that it is not difficult to obtain the necessary heat in the iron itself. Some of the principal difficulties, however, are the regulation or control of the heat in the iron, provision for proper combustion, the consumption of the minimum amount of gas, and the efficient thermal insulation of the iron body from the flexible gas supply tube, the mixer, and the handle.

My invention relates to improvements in the construction of sad-irons of the class mentioned, the objects of the improvement being to more perfectly control the heat in the iron, to improve combustion and at the same time use the minimum quantity of gas, and to more perfectly insulate the flexible gas supplying tube and mixer as well as the handle from the heat of the iron body. I attain these objects by the construction illustrated in the accompanying drawing, in which—

Figure 1 is a longitudinal vertical section on the median line illustrating an iron embodying my invented improvements. Fig. 2 is an underside view of the cover plate. Fig. 3 is a fragmentary view, the same being a transverse vertical section on the line 3—3 of Fig. 1. Fig. 4 is a fragmentary view, the same being a horizontal section through portions of the mixer, burner tube and the rear of the iron.

Throughout the several views similar numerals of reference indicate similar parts.

The numeral 1 indicates the hollow body of the iron, which is open at the top, the cover plate 2 being adapted to close said opening. Each of the two sides of the body 1 is provided at the top with an elongated recess at 3, said recess extending the greater portion of the length of said side. The cover plate 2 is provided with integral portions 4, which with said cover plate constitute exhaust flues extending from the outer edges of said cover plate toward the center thereof. The recesses at the top of the sides are adapted to accommodate the portions 4, as illustrated in Figs. 1 and 3. The purpose of providing elongated flues extending along the greater

portion of the sides of the iron and providing an uninterrupted passage for the exhaust of the burned gases is to permit the free and unmuffled play of said gases within 60 said iron, and to distribute as much as possible the heat of said gases. The advantage of a continuous flue over a series of flues or apertures will thus be readily apparent. The purpose of the arrangement of the portions 4 extending toward the center of the cover plate is to produce a bi-lateral distribution of the flame from the burner and a circulatory movement of the heated gases before being exhausted, the single, elongated 70 flue on each side of the iron body permitting such circulatory movement without the hindrance produced where longitudinal movement of the gases within said body is necessary before exhausting. The cover plate is 75 attached to the body of the iron by means of the screws 5 or their equivalents.

The rear end of the iron body is provided with a double wall portion formed by the inner wall 6 and the outer wall 7, the air 80 space 8 being thus provided. The said air space may extend from side to side of the iron or for a portion only of that distance, the latter construction being illustrated in the drawings. Near the bottom of 85 the iron body the said space 8 opens exteriorly at 9, said opening being adapted to permit the entrance of air into the space 8 in the bottom thereof. The space 8 at the top is continuous with a transversely, elongated aperture 10 in the cover plate, thus providing for the exhaust of air from the space 8 at the top thereof.

The burner 11 may be of any suitable construction, the preferable form being that 95 illustrated in the drawings, which consists of a tube closed at the forward end, provided with transverse slits 12 on the underside of the same, and the rear end provided with screw threads by which the said tube 100 may be screwed through a screw threaded aperture in the wall 6, into a similarly screw threaded aperture in the wall 7, as illustrated in Figs. 1 and 4. It will thus be seen that said burner will extend from the 105 exterior of the iron at the rear end through the space 8 into the interior of the hollow iron body.

The mixer 13 is attached exteriorly to the rear end of the iron by means of the screws 110 14 or their equivalents, a strip of asbestos or other thermal insulating material 15 be-

2

ing interposed between the iron body and the said mixer. Communication with the interior of the burner 11 is provided and an adjustable shutter 16 of ordinary construction may be employed for the purpose of controlling the amount of air admitted to the mixer. At a point opposite the aperture leading from the mixer to the burner is arranged a needle valve comprising a valve casing 17 and a needle 18 provided with a point adapted to fit within the interior of said casing in the usual manner, the other end of said needle being provided with screw threads for adjustment of said needle within the casing 17 and a slot 19 into which a screw driver or other instrument may be inserted for the purpose of making such adjustment. The integral lateral portion 20 of the valve casing constituting the gas conductor from the flexible supply tube 21 to the needle valve proper is provided at its end with external screw threads, while the collar 22 is provided with internal screw threads adapted for engagement therewith, said collar 22 serving to hold in place the nipple 23 to which the tube 21 is connected. Wound about the tube 21 in a spiral manner is a protecting wire 24 adapted to prevent injury of the tube 21, to prevent kinking of said tube, and the end of said wire extending about the lateral portion 20 and wound tightly thereon to assist in holding the tube 21 properly in place upon the nipple 23. In use the gas will enter the mixer through the needle valve, be mixed with the proper amount of air and projected into the burner 11 whence it will be delivered through the slits 12, forming a bi-lateral sheet of flame impinging primarily upon the bottom of the iron body, secondly upon the sides of said body, thirdly upon the undersides of the portions 4, and finally exhausting through the flues formed by said portions, thus completing a circulatory movement well adapted for the thorough utilization of the heat of the flame.

By reason of the space 8 the wall 7 will remain cooler than the wall 6, while the circulation of the air in said space will further aid in cooling the wall 7 as well as the rear end of the burner, the apertures at 9 and 10 providing free inlet and outlet of air. The asbestos insulation being imposed between the relatively cool wall 7 and the mixer 13 will further protect said mixer from the heat of the iron body and as a result the said mixer will be sufficiently cool to be conveniently adjusted while the tube 21 will not be injured by reason of over heated connections.

Upon the top of the cover plate 2 is arranged the shield 25 provided with the integral downwardly disposed lugs 26 adapted to enter corresponding dents in the cover plate, there being three lugs upon each

shield. The second shield 27 is provided with integral lugs 28 similarly arranged in dents in the upper surface of the shield 25. The screw 29 or its equivalent extends through the cover plate 2, the shield 25 and the shield 27 for the purpose of fastening the said plate and shields firmly together. Formed integrally with the shield 27 are the spaced handle arms 30 between which is arranged a handle 31 connected to said arms by means of the screw 32 or its equivalent. The obvious purpose of the shields 25 and 27 and their arrangement with air space between the shield 25 and the plate 2 and between the shield 27 and the shield 25 is to prevent the over-heating of the portion of the device closest to the handle 31, thereby permitting the operator to use the iron without inconvenience or harm.

I claim:

1. A gas heated sad-iron comprising a hollow body open at the top, a cover plate adapted to close said opening, the sides of said body provided at their top edges with elongated recesses, each recess extending for the greater portion of the length of the side, said cover plate provided with integral exhaust flues extending from the outer edges of the cover plate toward the center thereof, said recesses adapted to accommodate said flues, an inner wall and an outer wall at the rear end of said body, said walls having an air space between, the said space opening exteriorly at the bottom through said outer wall, said cover plate provided with a transversely elongated aperture registering with the upper opening of said air space, a burner extending from the exterior of said outer wall across said air space through said inner wall and through the interior of said iron body and means connected to said outer wall for conducting a mixture of gas and air into the interior of said burner.

2. A gas heated sad iron comprising a hollow iron body open at the top, a cover plate adapted to close said opening, the sides of said body provided at their top edges with elongated recesses, each recess extending for the greater portion of the length of the side, said cover plate provided with integral exhaust flues extending from the outer edges of said cover plate toward the center thereof, said recesses adapted to receive said flues, an inner wall and an outer wall at the rear end of said body, said walls having an air space between them, said space opening exteriorly at the bottom through said outer wall, said cover plate provided with a transversely elongated aperture registering with the upper opening of said air space, a burner extending from said outer wall across said air space, through said inner wall and into the interior of said iron body, a mixer attached exteriorly to said outer wall and provided with an aperture forming communica-

tion with the interior of said burner and means for conducting gas into said mixer.

3. In a device of the character described, a hollow iron body, exhaust flues arranged 5 at the top edges of the sides of said body and extending from the outer sides of said body inwardly, an inner wall and an outer wall at the rear end of said body, said walls having an air space between them, said 10 space having air inlet and outlet openings, a burner on the inside of said body and means connected to said outer wall for conducting gas into the interior of said burner.
4. In a device of the character described, 15 a hollow iron body provided with an in-

ternal burner, said body having spaced walls, the space between said walls being adapted to permit the passage of air between them, said space provided with air inlet and outlet openings and gas conducting 20 means attached to the outer wall and adapted to conduct gas into said burner.

In testimony that I claim the above, I have hereunto subscribed my name in the presence of two witnesses.

ALFRED H. DAVIES.
